DESIGN FOR A COMBINED CANOPY FOR A HAMMOCK AND SUPPORTING PILLARS THEREFOR

Omar John Schmidt, Fox Lake, Wis.

Application July 14, 1938, Serial No. 78,488

Term of patent 3½ years

To all whom it may concern:

Be it known that I, Omar John Schmidt, a citizen of the United States of America, residing at Fox Lake, in the county of Dodge and State of Wisconsin, have invented a new, original, and ornamental Design for a Combined Canopy for a Hammock and Supporting Pillars Therefor, of which the following is a specification; reference being had to the accompanying drawing, forming part thereof.

In the drawing:

I claim:

The ornamental design for a combined canopy for a hammock and supporting pillars therefor, as shown.

OMAR JOHN SCHMIDT.
